US0D1107857S

(12) **United States Design Patent** (10) **Patent No.:** **US D1,107,857 S**
(45) **Date of Patent:** **** Dec. 30, 2025**

(54) **ULTRASONIC PEST REPELLER**

(71) Applicant: **Xinping Peng**, Chenzhou (CN)

(72) Inventor: **Xinping Peng**, Chenzhou (CN)

(**) Term: **15 Years**

(21) Appl. No.: **29/934,162**

(22) Filed: **Mar. 24, 2024**

(30) **Foreign Application Priority Data**

Jan. 15, 2024 (CN) 202430024764.9

(51) **LOC (15) Cl.** **22-06**

(52) **U.S. Cl.**

USPC **D22/120**

(57) **CLAIM**

The ornamental design for an ultrasonic pest repeller, as shown and described.

DESCRIPTION

FIG. 1 is a front perspective view of an ultrasonic pest repeller, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the ultrasonic pest repeller, which form no part of the claimed design.

The unshaded area between the solid and dashed structures is form no part of the claimed design.

1 Claim, 8 Drawing Sheets
